US00D718600S

(12) **United States Design Patent**
Beyer

(10) **Patent No.:** **US D718,600 S**
(45) **Date of Patent:** **** Dec. 2, 2014**

(54) **ABRASIVE ARTICLE**

(75) Inventor: **Timothy T. Beyer**, Artarmon (AU)

(73) Assignee: **3M Innovative Properties Company**,
Saint Paul, MN (US)

(**) Term: **14 Years**

(21) Appl. No.: **29/419,424**

(22) Filed: **Apr. 27, 2012**

(30) **Foreign Application Priority Data**

Oct. 31, 2011 (EM) 001300057

(51) **LOC (10) Cl.** **08-05**

(52) **U.S. Cl.**

USPC **D8/90; D5/57**

(58) **Field of Classification Search**

USPC D5/3, 57; D8/90-94; D15/126; 428/43;
451/296, 527, 533

(57) **CLAIM**

The ornamental design for an abrasive article, as shown and described.

DESCRIPTION

FIG. 1 is a perspective view of an abrasive article showing an ornamental design in accordance with embodiment 1 of the present disclosure.

FIG. 2 is a top view of the abrasive article of FIG. 1;

FIG. 3 is a bottom view of the abrasive article of FIG. 1;

FIG. 4 is a front side view of the abrasive article of FIG. 1; and

FIG. 5 is a left side view of the abrasive article of FIG. 1.

The rear side view is identical to the front side view. The right side view is identical to the left side view.

FIG. 6 is a perspective view of an abrasive article showing an ornamental design in accordance with embodiment 2 of the present disclosure.

FIG. 7 is a top view of the abrasive article of FIG. 6;

FIG. 8 is a bottom view of the abrasive article of FIG. 6;

FIG. 9 is a front side view of the abrasive article of FIG. 6; and,

FIG. 10 is a left side view of the abrasive article of FIG. 6.

The rear side view is identical to the front side view. The right side view is identical to the left side view.

The broken lines in the drawings are directed to portions of the abrasive article that form no part of the claim.

1 Claim, 4 Drawing Sheets
